United States Patent Office.

WILLIAM KOPLIN, OF NEWCASTLE, PENNSYLVANIA.

Letters Patent No. 62,963, dated March 19, 1867.

IMPROVED MACHINE FOR MAKING CARRIAGE BOLTS.

The Schedule referred to in these Letters Patent and making part of the same.

TO ALL WHOM IT MAY CONCERN:

Be it known that I, WILLIAM KOPLIN, of Newcastle, in the county of Lawrence, and State of Pennsylvania, have invented a new and improved Machine for Making Carriage-Bolt Blanks; and I do hereby declare the following to be a full, clear, and exact description of the same, sufficient to enable any one skilled in the art to which the invention appertains, to make use of it, reference being had to the accompanying drawings, which form a part of this specification, and in which—

Figure 1 is a top view or plan.

Figure 2 is a side elevation.

Figure 3 is a front elevation.

Figure 4 is a perspective view of the moving carriage, with its set of dies.

Figure 5 is a view of the stationary die-holder, and dies mounted therein.

Figure 6 is a section to illustrate the relative positions of the pointer and cutter.

This machine cuts off a suitable length of bar, grasps and points it, upsets it, so as to form a square portion between the head and the thread, larger in diameter than the latter, and lastly, swages a raised head, completing the bolt blank, which is discharged by a hook, which drags it from its bed and drops it to the ground.

In the drawings, A represents the bed of the machine, from which rise standards B B, C C, D D. The standards B afford support for the main shaft E, in which are the cams, four in number, which give the suitable motions to the swages, acting upon the heated iron rod. The standards C support the swage which upsets and heads the bolt. The standards D support the frame or lever F which carries the pointer G, the swage H, and the swage I, whose purpose will be presently explained. The stationary jaw, J, holding certain dies, is attached to the frame or bed A, and the moving jaw K, with counterpart dies and a cutter, is journalled at L.

The operation of the machine is as follows: The heated iron rod is introduced between the recessed faces of the dies in the respective jaws, and extends to the face δ of the header. The main shaft E is rotated, and the cam O, acting by means of the arm M, and shaft N, upon the jaw K, causes the latter to approach the stationary jaw J. The cutter e first comes in contact with the iron and cuts off the piece, which is then grasped between the dies a a' b b' , which are placed in the respective jaws J K; the dies b b' merely hold it tightly, but the dies a a' reduce its size somewhat, in connection with the descending pointer G. The lever F, journalled in the standards, is vibrated by means of the cam P, on the main shaft E, and, as it descends, the pointer G, moving in an arc of a circle, pushes out the point of the bolt into the recess g , as shown in fig. 6, behind the edge of the cutter, the point of the swage G protruding into the said recess so as to render it necessary that the pointer should be again raised before the cutter is retracted. It is necessary that the bolt should have an enlarged square portion beneath the head, and this is formed between the dies c c' on the jaws J K, and the descending swages H on the lever F. The shank of the bolt being held between the dies a a' b b' ; and the space between the dies c c' being larger than the iron, the header δ is operated by the cam Q, on the main shaft E, and pressing against the end of the rod shortens and upsets it, causing it to swell in the space between the dies c c' . The die c is brought against one side of the bolt by the swage I, and the descending swage H presses against the upper surface, giving a square form to that portion of the bolt, after which the header δ being further advanced by the cam R, the head is formed of a shape corresponding to the form of the recess in the header face. The main shaft being further revolved, the lever F is raised by the spring S, the header withdrawn by the spring T, and the jaw J opening, the bolt is withdrawn by the hook W, and dropped upon the ground.

Having described my invention, what I claim as new, and desire to secure by Letters Patent, is—

1. The combination, with the dies a a' b b' , of the dies c H, operated as described to form the square on the bolt.

2. The die c, in combination with the swage I, on the lever F, operated as described.

To the above specification of my improvement in machines for making carriage bolts I have signed my hand this fourteenth day of July, 1866.

WM. KOPLIN.
